SOAKING PIT COVER WITH PROTECTED
SEALING MEANS

Robert W. Higgins, Evanston, Ill., assignor to
M. H. Detrick Company, Chicago, Ill., a corpora-
tion of Delaware

Application November 25, 1946, Serial No. 712,148

6 Claims. (Cl. 110—173)

1

The present invention relates to covers for soaking pits.

A soaking pit is one of a series of heating furnaces used in the steel industry for preparing products for rolling and shaping operations. Normally they constitute large, brick-lined chambers placed below the level of a charging floor. The top of the pit is left entirely open and is closed by a brick-lined removable cover, known as a soaking pit cover. It is this type of cover that forms the subject matter of the present invention.

The soaking pit is adapted to hold a plurality of steel ingots varying in number from about four to sixteen or more, depending upon the size of the pit and the ingots. Often a plurality of pits are disposed side by side, each pit being provided with its own separate cover.

During the period of operation of a pit of this type, temperatures of from 2200° F. to 2500° F. or more may exist in the pit and ingots may be charged into or removed from the pit while exceedingly high temperatures exist. The cover must be removed from the soaking pit during this charging or discharging operation and to accomplish this the cover is often raised vertically above the pit and moved laterally to one side.

Normally a cover of this sort is lined on its inner face with brick of the type that can stand extremely high temperatures. During the period when the cover is being removed or applied to a soaking pit the lower peripheral edge of the cover, as well as the outer face along the sides of the cover are subjected to high temperatures and the corrosive effect of hot gases that escape from the soaking pit. Heretofore these hot gases and exposures to high temperatures have caused the rim of the soaking pit cover to burn and break away, thereby requiring a very large amount of maintenance in the way of replacements in order to keep the covers in operative condition.

It is necessary for efficient operation of a soaking pit for the cover to provide a relatively effective seal so as to reduce to a minimum the escape of hot gases from the pit during the soaking period. This is accomplished by providing a sealing edge around the peripheral margin of the cover that becomes somewhat imbedded in a body of silica sand that is disposed completely around the perimeter of the soaking pit. The efficiency of this seal is reduced when the peripheral margin of the cover is burned or broken away as a result of exposure to the high temperatures and corrosive effect of the hot gases. The present invention is intended to overcome this difficulty and to materially lengthen the life of those portions of

2

the cover subjected to the high temperatures and hot gases. This life is extended while at the same time the effectiveness of the seal is maintained.

During normal operation of a soaking pit it is often desirable to maintain a pressure in the pit greater than atmospheric. Thus there may be some hot gases escaping through the seal between the soaking pit cover and the body of silica sand that surrounds the pit, and these hot gases are constantly passing across unprotected surfaces on the soaking pit cover. Where a plurality of soaking pits are disposed side by side the hot gases escaping from one soaking pit often subject the adjacent cover to the damaging effects of the high temperatures. The present invention is also intended to overcome this difficulty.

Thus the invention provides a soaking pit cover that can withstand extremely high temperatures, both during normal operation of the soaking pit to which it is applied and during the periods when the cover is being removed or applied to the pit. The life of the present soaking pit cover is substantially greater than that of previous covers and the maintenance problem is reduced to a minimum. This is all accomplished in a relatively simple manner at low costs.

The foregoing constitute some of the principal objects of the present invention, others of which will become apparent from the following description and the drawings, in which

Fig. 1 is a vertical sectional view through a soaking pit and a soaking pit cover, portions of the cover being shown in elevation and the soaking pit being illustrated more or less diagrammatically;

Fig. 2 is an enlarged top plan view of the soaking pit cover per se, a portion of the cover being broken away to illustrate the liner;

Fig. 3 is an enlarged longitudinal vertical sectional view taken through the cover of Fig. 2 and illustrating in addition a fragment of the soaking pit below the cover so as to illustrate the seal;

Fig. 4 is an enlarged fragmentary detail sectional view taken vertically through the cover and illustrating a seal casting applied to the cover;

Fig. 5 is a top plan view of one of the seal castings illustrated in previous figures;

Fig. 6 is a front elevational view of the casting shown in Fig. 5;

Fig. 7 is an end elevational view of the casting shown in Fig. 6;

Fig. 8 is a more or less diagrammatic bottom plan view of one corner only of a soaking pit cover embodying the present invention;

Fig. 9 is a view corresponding to Fig. 4 but illustrating a modified embodiment of the invention;

Fig. 10 is a horizontal sectional view through a portion of the cover, the view being taken on the line 10—10 of Fig. 9; and

Fig. 11 is a view corresponding more or less with Fig. 9 but illustrating still another embodiment of the invention.

For purposes of illustration certain embodiments of the invention have been selected, it being recognized, however, that many modifications may be made in the specific embodiments shown without departing from the intended scope of the invention.

Referring to Fig. 1 of the drawings the invention is illustrated in conjunction with a soaking pit generally indicated at 20. The soaking pit, per se, forms no part of the present invention, and is illustrated only for the purpose of showing the relationship between the cover and a pit upon which it may be used. As shown in Fig. 1 the soaking pit 20 comprises generally a pit 21 formed by vertical walls 22 that are arranged in the form of a rectangle. As shown the pit 21 is rectangular in shape and is provided with a bottom wall 23 that has an aperture 24 projecting upwardly therefrom. Apertures 25 are provided in at least certain of the side walls 22 and these apertures 25 lead to discharge chambers generally indicated at 26. A gas burner or the like 27 is provided adjacent to the lower end of the aperture 24 and is adapted to heat gases that are forced upwardly through the aperture 24 and into the pit 21 as indicated. These gases are caused to pass through the pit 21 and exhaust through apertures or ports 25 into the chambers 26 and finally leave the furnace through ducts 28 after passing over numerous baffles and the like.

The soaking pit 21 is adapted to contain a plurality of ingots 29 that are arranged in the pit as illustrated in Fig. 1 for example, in the path of the hot gases that are circulated through the pit.

The soaking pit cover forming the subject matter of the invention is illustrated generally at 30. This cover as best shown in Figs. 2 and 3 is rectangular in shape and comprises a pair of parallel, spaced I-beams 31 forming sides of the cover and I-beams 32 forming end walls of the cover. Intermediate spaced channel members 33 and spaced I-beams 34 form longitudinal and transverse reinforcing members that are rigidly secured to the side and end walls 31 and 32 respectively. Additional diagonal braces 35 are provided to further reinforce the structure of the cover.

As shown in Fig. 3 a heat resisting wall generally indicated at 36 is suspended from the cover structure and comprises generally a plurality of firebricks 37 suitably suspended from certain of the I-beams by means of hangers 38. As indicated in Figs. 2 and 3 these firebricks 37 are of various sizes and shapes and protect the entire inner faces of the structural members of the cover from the intense heat that exists in the soaking pit chamber 21.

Projecting downwardly from the I-beams 32 and 34 is an annular seal member generally indicated at 39 in Fig. 3 that comprises a channel member 40 (Figs. 3 and 4) that may be bolted or otherwise secured as at 41 to the lower flange of I-beams 32 or 31 as the case may be and a plurality of sealing units or castings 42. Each

of the castings 42 comprises a substantially horizontal upper flange 43 having a web 44 projecting downwardly therefrom as best indicated in Figs. 5 to 7 inclusive. The casting 42 is generally rectangular in elevation as illustrated in Fig. 6 and is provided with a plurality of reinforcing ribs 45 that extend from the upper flange 43 to a position adjacent to the bottom of the web 44. At the lower end of the web 44 is provided a sealing edge member 46 that extends for the full length of the sealing unit 42 and in cross section is substantially in the form of an isosceles trapezoid. The sealing edge 46 projects beyond both faces of the web 44 so as to provide an inner and outer shoulder portion 47 and 48 respectively. A plurality of lugs 49 project from the inner and outer faces of the web 44 and are spaced throughout the length of the unit 42. A plurality of slots 50 (Fig. 5) are provided in the upper flange 43 to each of the sealing units 42 and the units 42 are arranged in end to end relationship along the sides and ends of the cover, suspended by means of bolts 51 from the lower flange of the channel members 40. The bolts 51 pass through the slots 50 in the upper flange 43 of each of the sealing units 42 and the sealing units may be applied by merely hooking the unit in place on the bolts 51.

As best shown in Fig. 8 the sealing units 42 are spaced slightly apart so as to provide a slight space therebetween indicated at 52. As shown each face of the web 44 of each unit 42 is disposed inwardly with respect to the outermost edges of the castings (Fig. 7). It is also to be noted that the outer end of each of the lugs 49 is disposed inwardly with respect to the outermost edges of the castings. These faces of the web 44 are completely imbedded in a heat resisting compound, such as a pliable chrome ore refractory, that is applied in a plastic state and rammed in place so as to completely fill the pockets formed by the depressed faces of the web 44. This is illustrated best in Fig. 4, the plastic compound being shown at 53. This compound 53 is supported on the shoulders 47 and 48 of the sealing edge 46 (see Fig. 4) and completely covers the faces of the web 44 and imbeds the lugs 49. This compound has the property of taking an initial set on exposure to air and of hardening to a substantial degree upon exposure to high temperatures. When properly hardened the material becomes very hard and has the property of withstanding extremely high temperatures without deteriorating. Thus an effective protective coating is applied to the units or castings 42 that protects both the inner and outer faces thereof.

The heat resisting compound is also applied to the spaces 52 between the adjacent sealing units 42 as shown at 54 (Fig. 8). Each of the sealing units 42 may have its inner ends bevelled as shown at 55 so that the castings may either be arranged side by side or may be used as corner castings disposed at 90° with respect to each other. In either event the heat resisting compound completely fills the spaces between the castings.

As shown in Fig. 3 the walls 22 of the soaking pit are each provided with a trough 56 that completely encircles the opening into the soaking pit chamber 21. This trough 56 is disposed directly below the annular seal member 39 and is filled with a quantity of sand 57 into which the seal castings 42 are partially imbedded when the pit cover is in place. In this manner an effective

seal is provided so as to eliminate as much as possible the escape of hot gases from the soaking pit chamber 21.

As shown in Fig. 9 it may be desirable to extend the heat resisting compound protective coating above the sealing units 42 so as to protect additional portions of the structure. This may be accomplished by securing a plurality of web members 58 to the I-beams 31 or 32 as the case may be by means of welding or the like indicated at 59 and to each of these web members 58 is secured an angle plate 60 that is provided with ears 61 that are adapted to receive bolts 62 that pass through the ears and the webs 58. Each angle plate 60 extends the full distance between adjacent web members 58 (see Fig. 10). Projecting outwardly from the outer face of each of the angle plates 60 are a plurality of lugs 64 that are spaced throughout the length of the height of the plate. In this embodiment of the invention the heat resisting compound 65 is applied to a much greater depth on each of the sealing units 42 and is brought out to a position slightly beyond the outer plane of the lugs 64. This compound is spread over the entire face of the angle plates 60 and fills the spaces between adjacent angle plates 60 as illustrated in Fig. 10. Thus a protective coating is applied to the side and end walls of the cover to a position well up along the I-beams 31 and 32.

Still another embodiment of the invention is illustrated in Fig. 11. In this form of the invention no channel member corresponding to member 40 in Fig. 4 is provided. Instead each of the sealing units 42 is provided with a taller web portion 44 so that the unit 52 in this instance is applied directly to the lower flange of each of the I-beam members 31 or 32 as the case may be. The heat resisting compound is applied to both inner and outer faces of the sealing units 42 as previously described, but in this instance the protective coating thus formed extends upwardly to a position just below I-beam 32.

Thus there is provided a sealing ring that completely covers the lower peripheral margin of the soaking pit cover 30. This ring is able to withstand extremely high temperatures and the corrosive effect of the hot gases that normally escape from a soaking pit of the type described. The life of the sealing units or castings 42 is thereby greatly increased. To replace a casting 42 it is merely necessary to fracture the heat resisting compound protective coating so as to make it possible to remove the faulty casting and replace it with a new casting. A new coating of heat resisting compound is then applied to this new casting and after proper seasoning of this material the cover is again ready for use.

I claim:

1. A soaking pit cover including a tapered seal portion projecting downwardly along the periphery of the cover, said seal portion comprising a plurality of seal units arranged substantially end to end and secured to the cover, each unit being tapered downwardly to a relatively narrow edge, a plurality of lugs projecting from the faces of the unit, and a protective covering held on each face by the lugs and adapted to withstand high temperatures.

2. A soaking pit cover including a tapered seal portion projecting downwardly along the periphery of the cover, said seal portion comprising

a plurality of seal units arranged substantially end to end and secured to the cover, each unit comprising an upper, substantially horizontal flange, a downwardly projecting web, the lower edge of the web providing a sealing edge, the sealing edge providing a shoulder along its edge facing the flange, and material at least partially supported on the shoulder and covering the faces of the web and adapted to withstand high temperatures.

3. A soaking pit cover including a tapered seal portion projecting downwardly along the periphery of the cover, said seal portion comprising a plurality of seal units arranged substantially end to end and secured to the cover, each unit comprising a downwardly projecting web having disposed at its lower edge a sealing edge, a plurality of lugs projecting from at least one face of the web, a shoulder provided at the lower end of the web and disposed on the same side of the web as the lugs, and material supported on the shoulder and by the lugs and covering the adjacent face of the web, said material being adapted to withstand high temperatures.

4. A soaking pit cover sealing unit comprising a metallic web portion having a tapered lower edge extending the length of the unit and forming a relatively narrow sealing edge, a shoulder provided adjacent to the sealing edge on each side of the web and extending the length of the unit, a plurality of lugs projecting from the faces of the unit, and a protective covering held on each face by the lugs and the adjacent shoulder and adapted to withstand high temperatures.

5. A soaking pit cover sealing unit comprising a metallic web portion having a tapered lower edge extending the length of the unit and forming a relatively narrow sealing edge, a shoulder provided adjacent to the sealing edge on each side of the web and extending the length of the unit, a plurality of outwardly projecting members on the faces of the unit, and lugs projecting from the faces of the unit, and a protective covering held on each face by the lugs and the adjacent shoulder and adapted to withstand high temperatures.

6. A soaking pit cover including a tapered seal portion projecting downwardly along the periphery of the cover, said seal portion comprising a plurality of seal units arranged substantially end to end and secured to the cover, each unit being tapered downwardly to a relatively narrow edge, a plurality of outwardly projecting members on the faces of the unit and lugs projecting from the faces of the unit, and a protective covering held on each face by the lugs and adapted to withstand high temperatures.

ROBERT W. HIGGINS.
